UNITED STATES PATENT OFFICE.

HOSEA KENNEDY, OF ROSE POINT, PENNSYLVANIA.

COMBINED COMMODE AND EARTH-CLOSET.

SPECIFICATION forming part of Letters Patent No. 268,689, dated December 5, 1882.

Application filed August 25, 1882. (No model.)

To all whom it may concern:

Be it known that I, HOSEA KENNEDY, of Rose Point, in the county of Lawrence and State of Pennsylvania, have invented a new and useful Improvement in Combined Commode and Earth-Closet, which improvement is fully set forth in the following specification and accompanying drawings, in which—

Figure 1 is a front perspective view of my improved commode and earth-closet, partly in section; Fig. 2, a front perspective with the swinging seat turned on its pivot. Fig. 3 is a perspective view of the lower part of the commode with the swinging seat removed; and Fig. 4, a perspective view, partly in section, of the earth receptacle or chamber.

The object of my invention is to provide a combined commode and earth-closet, so arranged that the contents of the commode may be readily and quickly covered with earth, dust, or other deodorizing agent, thus preventing the escape of noxious gases after use.

It consists in providing a suitable box or chamber with a hinged or swinging lid. In one part of this lid is the usual aperture provided in all commodes, and by the side of this aperture is a box or chamber to receive dust, earth, or deodorizing material, and provided with a perforated bottom and a valve and stem. The lid, thus arranged, may be turned to bring the earth-chamber over the commode or to bring the aperture over the commode, all of which will now be set forth in detail.

In the accompanying drawings, A represents a box or receptacle of suitable size to contain a metallic or other vessel, B. Projecting out from the rear side of the box is a bracket, C, having at its outer end a stud or lug, D.

The lid or top E is formed preferably in the shape of a quadrant or sector of a circle, and is hinged to the stud D of the bracket C in such a manner that the body of the lid covers the box or receptacle A, as shown in Figs. 1 and 2.

One end of the lid is provided with the usual seat-aperture, F, for the use of the occupant. The other end or portion of the lid E is provided with a box or chamber, G, in such a position that when the lid is turned on its hinge the chamber G will be directly over the metallic vessel B within the box A, or in the position occupied by the aperture F.

The lid E is provided with perforations H within the chamber G, through which the dirt

may pass from the chamber G into the vessel B.

I represents a perforated head in the chamber G, to which is attached a stem or rod, J, which passes up through the lid or top K of the chamber. In operation this perforated head I rests on the bottom of the chamber G and dirt placed thereon, and when it is desired to deposit dirt on the contents of the vessel B it is sifted through the perforations by agitating the perforated head I.

The operation is as follows: Fig. 1 represents the position of the device when ready for use in the bed-chamber. After use the lid E is turned so as to assume the position indicated in Fig. 2, in which the dirt-chamber G is directly above the vessel B. The valve stem or rod J is then agitated, which causes a deposit of dirt, ashes, or other material contained in the chamber to fall on the contents of the vessel B, thereby preventing the formation and escape of noxious gases and thoroughly deodorizing the soil.

The vessel B may be removed and emptied at any time by turning the lid so as to gain access to the interior of the box A.

It is obvious that the vessel B may be made of stoneware or cast; but tin, zinc, or sheet-iron is preferable, as it is more serviceable for handling.

Having described my invention, what I claim is—

1. In earth-closets, the lid having a dirt or earth receptacle, G, perforated within, as shown, in combination with a perforated head, I, having a stem or rod, J, whereby the dirt or other contents of the receptacle may be sifted through, substantially as herein set forth.

2. In earth-closets, the box A, having the bracket C, containing the lug or pin D, and the vessel B, within the box, in combination with the hinged lid E, having at one side the seat-aperture F and at the other end or side the dirt-receptacle having the perforated bottom, and the perforated head I, having the stem or rod J, substantially as and for the purpose herein shown.

In testimony that I claim the foregoing I have hereunto set my hand, this 5th day of August, 1882, in the presence of witnesses.

HOSEA KENNEDY.
